UNITED STATES PATENT OFFICE.

ROBERT EMIAH DOWNIE, OF CLINTON, ASSIGNOR OF ONE-HALF TO GEORGE A. HOUSTON, OF BELOIT, WISCONSIN.

FIRE-ESCAPE.

SPECIFICATION forming part of Letters Patent No. 295,527, dated March 25, 1884.

Application filed November 7, 1883. (No model.)

To all whom it may concern:

Be it known that I, ROBERT E. DOWNIE, a citizen of the United States, and residing at Clinton, in the county of Rock and State of Wisconsin, have invented a certain new and useful Improvement in Fire-Escapes, which is fully set forth in the following specification, reference being had to the accompanying drawings, in which—

10 Figure 1 represents a vertical section of my fire-escape, the slide on the rope being shown in position to slide freely thereon; Fig. 2, a side elevation of the same; and Fig. 3, a similar sectional view of the same, showing the 15 slide clamped to the rope.

My invention relates to that class of fire-escapes in which there is a rope secured at its upper end to some fixed part of the building, either in the several rooms or elsewhere, and 20 a slide applied thereto, to which the carrier or sling is attached, and which is provided with suitable devices for clamping the rope, as may be desired, to regulate the downward movement.

25 I will proceed to describe in detail the construction and operation of the devices by means of which I have embodied my invention in practical form in one way, and will then point out definitely in the claims the 30 special improvements which I believe to be new and wish to protect by Letters Patent.

In the drawings, A represents the rope, which is secured at its upper end, in any usual way, at the desired point for operation, this 35 rope being arranged and applied for use in the usual way for this class of escapes. To this rope a slide, B, is applied, which is composed of two independent parts connected together when applied to the rope, as will be described 40 presently. One part, C, is provided with openings c, arranged a short distance apart, and extending from the inner edge through to the outer edge, and between these openings is a curved or circular boss, c', projecting slightly 45 beyond the main outer edge of this slide. These openings are adapted to permit the rope to be passed through them and around the curved boss on the outside. This member of the slide is also provided with short interior

grooves, c², at each end, as shown in Figs. 1 and 50 3 of the drawings. The other member, D, of the slide is adapted at its inner edge to fit the corresponding edge of the member C, the inner faces of the two being straight and plain for this purpose, except where grooved or 55 perforated. Near each end of the piece D two holes, d, pass through it from inside to outside, and between each pair of apertures is a curved or circular boss, d', around which the 60 rope may be passed, being carried through the holes for this purpose. The distance between the two interior holes, d, is substantially the same as that between the two holes c in the corresponding portion of the slide, so that these apertures in the two members 65 will register when the parts are brought into position opposite to each other, as shown in Fig. 1 of the drawings. At each end of the member D is also a short interior groove, d², which, with the corresponding grooves on the 70 opposite member, makes a circular opening when the two parts are brought together, admitting the entrance of the rope between the two. A bail, E, is pivoted to one member of the slide, preferably the part C, as shown in 75 the drawings, and to this bail a sling, F, or any other suitable receiver, is attached. A short lever, G, is pivoted at one end to the piece C, the inner face of which, at its central portion, is recessed for this purpose, and extends outward through a slot, d³, in the opposite piece, 80 D, and is secured to the latter by a pivot-pin, g, the lever having preferably a short slot, g', through which this pin passes. The lever projects out at one side of the slide, as shown in 85 the drawings, and must be within easy reach of a person in the sling, basket, or whatever attachment is used as a carrier. It will be seen from this description that the two parts of the slide are connected together by this 90 lever, and at the same time that one can be moved upon the other by operating the lever, and that by such relative movement the central openings in the two parts may be made to register or not, as desired. The slide is applied to the rope by passing the latter in at one end, then out through the first opening in the part D, around the adjacent boss, back 95

through the opening in this part on the other side of the boss and the corresponding opening in the opposite member, C, of the slide, which registers with the former, then around 5 the boss c' and back through the corresponding registering openings in the two members of the slide on the other side of the boss, and then around the boss d' at the other end of the member D, and inward through the last opening d in this end, and out through the other end of the slide, as clearly shown in Figs. 1 and 3 of the drawings. Now, it will be seen that the two parts of the slide are also connected by the rope which winds in and out 10 around them. It is evident that when the two parts are in the position shown in Fig. 1, with the central openings registering, the slide will slip down on the rope quite easily if any weight is applied; but it is also evident that as soon 15 as weight is brought upon the bail a downward strain is produced on the member of the slide to which the bail is attached, thereby pulling this member downward independently of its companion. This will of course tend to 20 destroy the register of the central openings of the slide, and thus clamp the rope between the two parts by biting it at the openings, as shown in Fig. 3 of the drawings. This bite is 25 so short and sharp that the weight of a person 30 on the bail will clamp the slide to the rope, so that it will be held from all downward movement, and the greater the weight obviously the stronger will be the clamping force exerted. It will thus be seen that the clamping of the 35 slide to the rope is automatic and effected as soon as a weight is brought upon the bail by a person getting into the carrier attached thereto, so that there is no danger of the sudden and unexpected movement of the slide 40 downward on the rope. This movement is accomplished only by operating the lever, and so is completely under the control of the person in the carrier, who seizes the lever, and by a downward pull thereon, which tends to bring 45 the members of the slide into registry again, releases the clamp more or less, thereby permitting the slide to move downward on the rope. The rapidity of the downward movement is completely under the control of the 50 occupant of the carrier, the lever being worked to release the clamp more or less, as may be desired, thereby regulating the movement of the slide on the rope exactly as the person wishes.

55 Now, it is apparent that it will be desirable to prevent the slide from running too freely down the rope by increasing the pull on the lever, which may be very liable to occur in the excitement and fright occasioned by a 60 fire. If the clamp were so constructed that an increased pull on the lever would only release it more and more, there would be danger of a descent so rapid as to produce injury to the person. It is obvious in my device 65 that this cannot take place, for if the pull on the lever is increased so as to carry up-

ward the bail portion beyond the point of registry there will at once begin a clamping effect in the other direction from that described above, and so the stronger pull on the 70 lever will actually operate to increase the friction, and so slacken the movement of the slide on the rope. The appliance, therefore, is perfectly safe. The slide will only move downward on the rope when the rope-apertures of the two parts are substantially in registry, and any movement of the two parts of the slide in either direction to disturb this registry will operate to clamp the rope, and either stop the movement of the slide altogether or slacken it, as may be desired. Pull sufficiently on the lever to register the rope-holes, and the slide moves downward. Let go of the lever, or pull too hard upon it, and the slide is clamped on the rope and movement 85 stopped or diminished.

I am aware that fire-escapes of this class are known; but I believe my device contains new features in making the operation of the clamp entirely automatic and certain in action whenever a person gets into the carrier, and also in placing the operation of the clamp entirely within the control of the person on the escape by the ready and easy movement of a hand-lever, by means of which the descent 90 to the ground may be regulated at will and accomplished with perfect safety.

I do not limit myself to the application of the bail to the member C of the clamp, as shown in the drawings, for it is evident that 100 the attachment may be made to either of the parts C and D, the lever arrangement being correspondingly changed. It is, however, more convenient to make this attachment to the part C, as shown in the drawings, as the 105 arrangement of the lever is better accommodated by the unoccupied central portion of the member D. I do not wish to be understood, either, as limiting myself to the precise construction and arrangement of the two-part slide, for obviously changes may be made in this respect, and also in the particular arrangement of the slide on the rope, and yet the main features of my improvement, as set forth above, may be retained with all the advantages pertaining thereto.

Having thus described my invention, what I claim as new, and desire to secure by Letters Patent, is—

1. In a fire-escape, a slide composed of two 110 independent parts arranged side by side, with their inner faces flat and in contact, in combination with a suspended rope passing in and out through both parts of the slide, a carrier attached to one member of the slide, 115 and a lever pivoted at one end to one member of the slide, and having its fulcrum on the other member, substantially as and for the purposes set forth.

2. In a fire-escape, the rope A, in combination with a slide member, C, provided with apertures c and boss c' , the companion slide

member D, provided with apertures *d* and bosses *d'*, and the bail E, attached to one member of the slide, substantially as and for the purposes set forth.

5. 3. In a fire-escape, the suspended rope A, in combination with the slide B, composed of the two members C and D, constructed substantially as specified, the bail E, attached to

one of the members of the slide, and the lever G, substantially as and for the purposes set forth.
